UNITED STATES PATENT OFFICE.

LESTER BRUMBAUGH, OF MIDDLEBRANCH, OHIO.

SIGNALING DEVICE.

Application filed October 2, 1923. Serial No. 666,213.

To all whom it may concern:

Be it known that I, LESTER BRUMBAUGH, a citizen of the United States, residing at Middlebranch, in the county of Stark and

5 State of Ohio, have invented certain new and useful Improvements in Signaling Devices, of which the following is a specification.

This invention relates to certain new and 10 useful improvements in signaling devices, and has particular reference to means for indicating to a driver approaching a road intersection or curve, that a vehicle is approaching such intersection or curve from 15 the opposite direction.

The primary object of the invention is to provide a device of the above kind, particularly adapted for use at night and depending for its operation upon its reflection 20 of the light projected thereon from the headlight of the approaching vehicle.

An object of the invention is to provide a device of the above kind, which embraces the desired qualities of simplicity and 25 durability of construction, as well as efficiency in operation.

A further object of the invention is to 30 provide a signaling device wherein the light from the headlights of a motor vehicle approaching a road intersection or curve is projected at an angle to the line of travel of said vehicle in the direction in which said road curve or intersection leads, provision being made for adjustment of the reflecting 35 element within limited distances as required in the practical use of the device.

A further object of the invention is to 40 provide for the notification of the fact that the driver is approaching such curve or intersection, and at the same time apprise others coming in opposite direction that such approach is made.

With the above general objects in view, 45 and others that will become apparent as the nature of the invention is better understood, the same consists in the novel form, combination and arrangement of parts hereinafter more fully described, shown in the accompanying drawing and claimed.

50 In the drawing, wherein like reference characters indicate corresponding parts throughout the several views,

Figure 1 is a front elevational view of a 55 signaling device construction in accordance with the present invention.

Figure 2 is a side elevational view thereof.

Figure 3 is a horizontal substantially central longitudinal sectional view of the device, shown in Figure 1, drawn on a smaller scale.

60 Figure 4 is a view similar to Figure 3, illustrating a slight modification of the invention, and

Figure 5 is a view similar to Figures 3 and 4 of a still further modification.

65 Referring more in detail to the drawing, the present invention embodies a casing 5, preferably of cylindrical form, and suitably supported, at the required elevation in a horizontal position by means of a post or standard 6 of any desired form. The casing 5 is open at one or both ends, depending upon the number of directions in which the light is required to be reflected, and the open end or ends is or are closed by means of 70 green tinted or colored reflectors or mirrors 7 each in the form of a disc having a relatively large central opening 8, and suitably removably held in place by means of a fastening ring 9, similar to the manner of attaching lenses to headlights.

75 Arranged within the casing 5 is a suitable reflector 10, and the casing is provided with an opening or openings as at 11, at one or more sides of the reflector 10, through which 80 the light may be projected at an angle to the path at which it enters the casing 5 through the opening 8 of the reflector 7.

85 Referring to the form of the invention shown in Figures 1 and 3, specifically, the 90 casing is closed at one end by means of an opaque wall 12, and has the other end thereof provided with a green colored reflector disc 7, having the central opening 8, the reflector 10 being of substantially V-shape 95 and mounted with its guide members vertically disposed and converging at a point indicated at 13 rearwardly of the central portion of the opening 8. Also, the openings 11 are provided in the sides of the casing 5, 100 in position to permit the passage of light rays from a mirror 10 in either direction. The V-shaped mirror is preferably mounted by hinging the same as at 14, for horizontal swinging movement at the pointed or narrow end thereof, so that the mirror may be 105 adjusted for reflecting the light at the desired angle when the cross road does not extend exactly at right angles to the road which the mirror 7 faces. The openings 11 are preferably closed, by means of screen elements or grills 15, so that the mirror 10

is effectively protected against breakage by flying objects or missiles that may be carelessly thrown. In the use of this form of the invention which is especially useful in points where a road terminates at an intersecting road that extends in opposite directions at right angles thereto, the casing is supported so that the openings 11 are opposed to the opposite portions of the intersecting roads with the reflector disc 7 facing the road that terminates at said intersecting road. When thus arranged, it will be apparent that the lights from the headlight of a motor vehicle directly approaching the reflector 7 will pass through the opening 8 on to the opposite sides of the mirror 10 and be thereby reflected through both of the openings 11 so as to advise drivers of vehicles approaching the sides of the device, that the first mentioned vehicle is approaching. Also, the light of said headlight shining upon said mirror 7 will advise the driver of the vehicle having these headlights that the intersection is about to be approached, thus serving as a warning at all three portions of the road.

The device shown in Figure 4 is identically of the same construction as that shown in Figures 1 to 3, except that a different form of mirror 10' is employed, the last mentioned mirror being of single flat form and disposed obliquely within the casing 5 to only project the light through one side opening 11, when the road does not extend in a direction from the other side of the device, the remaining opening in the battery casing being unnecessary, at this time. The mirror 10' is pivotally mounted upon a vertical axis as at 14' so that the angle of the same may be changed as conditions may require or dictate. The operation is substantially the same as above outlined in general aspect.

In the form of the invention shown in Figure 5, the casing 5 is open at both ends and has each end thereof closed by means of a centrally apertured mirror 7, the mirror 10" within the casing being of substantially diamond shape as to reflect light through opposite sides from the headlights of motor vehicles approaching either end of the casing. This form of the invention is particularly useful where intersecting roads extend from each other in both directions, it being necessary to provide a pair of openings in each side of the casing 5 in this form of the device, through which the reflector device may pass from the four operative portions of the mirror 10".

In practice, it is preferred to make the mirrors 10, 10' and 10" of red color, so as to serve as a danger signal when illuminated by the light from the headlights of approaching vehicles.

From the foregoing description, it is be-

lieved that the construction and operation, as well as the advantages of the present invention will be readily understood and appreciated by those skilled in the art.

Minor changes may be made without departing from the spirit and scope of the invention as claimed.

What I claim as new is:

1. A light reflecting traffic signal of the character described comprising a casing having an open end adapted to face one road at a road curve or intersection, a centrally apertured mirror closing the end of said casing, said casing having an opening in a side thereof, and a mirror within the casing in position to receive light rays entering the opening in the first named mirror and to project the same through said opening in the side of the casing.

2. A light reflecting traffic signal of the character described comprising a casing having an open end adapted to face one road at a road curve or intersection, a centrally apertured mirror closing the end of said casing, said casing having an opening in a side thereof, a mirror within the casing in position to receive light rays entering the opening in the first named mirror and to project the same through said opening in the side of the casing, said first named mirror being in the form of a disc and colored one color, and said second named mirror being colored a different color.

3. A light reflecting traffic signal of the character described comprising a casing having an open end adapted to face one road at a road curve or intersection, a centrally apertured mirror closing the end of said casing, said casing having an opening in a side thereof, a mirror within the casing in position to receive light rays entering the opening in the first named mirror and to project the same through said opening in the side of the casing, said first named mirror being in the form of a disc and colored one color, said second named mirror being colored a different color, and a screen closing the side opening of the casing for preventing entrance of objects therethrough.

4. A light reflecting traffic signal of the character described comprising a casing having an open end adapted to face one road at a road curve or intersection, a centrally apertured mirror closing the end of said casing, said casing having an opening in a side thereof, a mirror within the casing in position to receive light rays entering the opening in the first named mirror and to project the same through said opening in the side of the casing, said first named mirror being in the form of a disc and colored one color, said second named mirror being colored a different color, said mirror being obliquely disposed with respect to the longitudinal axis of the casing, and means mount-

ing said mirror within the casing for permitting swinging of the same upon a vertical axis, whereby the angular relation of the mirror to the longitudinal axis of the 5 casing may be adjusted.

5. A light reflecting traffic signal of the character described comprising a casing having an open end adapted to face one road at a road curve or intersection, a centrally apertured mirror closing the end of 10 said casing, said casing having an opening in a side thereof, a mirror within the casing in position to receive light rays entering the opening in the first named mirror

and to project the same through said opening in the side of the casing, said first named mirror being in the form of a disc and colored one color, and said second named mirror being colored a different color, 15 said second named mirror comprising diverging members extending obliquely of the casing and seating at their ends nearest the first named reflector substantially centrally of the casing and the opening in the first named reflector. 20 25

In testimony whereof I affix my signature.

LESTER BRUMBAUGH.
